DESIGN FOR A SATCHEL.

SPECIFICATION forming part of Design No. 13,994, dated June 19, 1883.
Application filed April 5, 1883. Term of patent 3½ years.

DESIGN FOR A SATCHEL.

SPECIFICATION forming part of Design No. 13,994, dated June 19, 1883.

Application filed April 5, 1883. Term of patent 3½ years.

UNITED STATES PATENT OFFICE.

ISIDOR WALLACH, OF NEW YORK, N. Y.

DESIGN FOR A SATCHEL.

SPECIFICATION forming part of Design No. 13,994, dated June 19, 1883.

Application filed April 5, 1883. Term of patent 3½ years.

To all whom it may concern:

Be it known that I, ISIDOR WALLACH, of New York, in the county and State of New York, have invented a new and original Design for Satchels, of which the following is a specification, reference being had to the accompanying photographic illustration, making a part of this specification.

Figure 1 is a perspective view of my new satchel, showing it opened. Fig. 2 is a similar view thereof, showing it closed.

This invention relates to a new form of satchel; and it consists in the novel configuration of the end pieces thereof, as hereinafter more fully pointed out.

In the accompanying photograph, the letters A B represent the two end pieces at one end

of the satchel, and have each a substantially straight outer edge, *a*, a narrow upper edge, *b*, a somewhat broader lower edge, *d*, the inner edge, *e*, and shoulder *f* at or near its middle, as shown. The form of the parts is the same at each end of the satchel. When the satchel is closed, the edges *e e* of the parts A B below the shoulders *f* are in contact, as shown. 25

I claim—

The design for the satchel, the same consisting of the end pieces, A B, having inner edges, *e*, with steps or shoulders *f* thereon, substantially as shown.

ISIDOR WALLACH.

Witnesses:

HARRY SMITH,

WILLY G. E. SCHULTZ.
